UNITED STATES PATENT OFFICE.

BIRGER LJUNGSTRÖM, OF STOCKHOLM, SWEDEN.

VANE-RING FOR TURBINES.

933,379.

Specification of Letters Patent. Patented Sept. 7, 1909.

Application filed March 16, 1908. Serial No. 421,381.

To all whom it may concern:

Be it known that I, BIRGER LJUNGSTRÖM, of 18 Grefmagnigatan, Stockholm, Sweden, a subject of the King of Sweden, have invented certain new and useful Improvements in Vane-Rings for Turbines; and I do hereby declare the following to be a full, clear, and exact description of the invention, such as will enable others skilled in the art 10 to which it appertains to make and use the same, reference being had to the accompanying drawings, and to figures of reference marked thereon, which form a part of this specification.

15 This invention relates to improvements in vane rings for fluid pressure turbines in which the rings are composed of a series of vanes secured to connecting strips so as to form a perforated cylinder, and the invention 20 has for its object to provide reinforcing or stiffening rings for said strips, and consists in forming projections on the strips and rings adapted to be connected to one another by swaging the edges or by distorting 25 a separate securing member to form a connection.

In the drawing accompanying and forming part of this specification I have shown in detail certain advantageous forms of embodiment of the invention, which, to enable those skilled in the art to practice the same, will be set forth in detail in the following 30 description, while the novelty of the invention will be included in the claims succeeding said description.

Referring to said drawings—Figures 1 and 2 are sectional and side views respectively, of a portion of a vane ring for an axial turbine illustrating one form of connection between the connecting strips and reinforcing or stiffening members. Fig. 3 is a cross section of a modified form of stiffening member and illustrating a roller as a means for clamping said stiffening member to a connecting strip. Figs. 4, 6 and 40 7 are similar views, illustrating modified forms of connecting means, and Fig. 5 is a cross section of a radial turbine provided with further modified forms of connections 45 between the connecting strip and stiffening member.

In the vane ring illustrated in Figs. 1 and 2 the numeral 1 designates the vanes, preferably crescent-shaped in cross section, and 50 connected in series by means of strips 3

which have slots formed therein conforming to the cross section of the vanes. The ends of the vanes project into the slots of the strips and are secured to said strips by welding, which may be carried out by means of a 60 flame from a bellows pipe or from an acetylene or hydrogen burner, or by means of an electric voltaic arc brought into contact with the projecting ends and causing that portion of the vanes to smelt. 65

The strips 3 are preferably in the form of rings or segments, or they may first have the form of straight strips in which the slots are made, and when the vane ends are fastened in the manner described said strips 70 are bent into the form of a ring. The connecting members or strips 3 are then secured to thicker stiffening or reinforcing bands or rings 4, and any portion of the strip 3 which projects beyond the edges of the 75 vanes 1 and all projecting edges or unevenness may be worked down in any manner, as by bending or grinding, until the strips 3 conform to the width of the vanes.

The stiffening rings may be provided with 80 concentric projecting edges, which are, by the aid of suitable tools, such as roll 10 shown in Fig. 3, made to change their form after the ring has been placed in proper position and caused to engage and lock with 85 undercut, concentric edges on the connecting strip.

As shown at the upper portion of Fig. 1, the connection between the stiffening or reinforcing ring and connecting strip is effected 90 by providing a flange, as 8, on one edge (shown on an enlarged scale in Fig. 3) of the stiffening ring 4 which fits into a corresponding recess formed in the strip 3. The other edge of said ring has a lateral projection 9, 95 which is swaged or pressed down, preferably by means of a roll 10 into the position indicated by dotted lines (Fig. 3,) against a corresponding surface on strip 3 and holds the latter locked against the shoulder 8. 100

At the lower portion of Fig. 1 the ring 4 is shown as provided with a longitudinal groove 11 to receive the strip 3, whose periphery conforms to the shape of the groove in the ring, and is locked therein by means of 105 the projection 9 on the latter being swaged or pressed into the position shown. The central stiffening ring shown in Fig. 1 is connected to the strips 3 by means of a separate securing member or ring 7 inserted between the 110

central ring and the strips. Such securing members may be of drawn wire, soft steel, brass, copper, nickel or any suitable material of suitable profile, and the arrangement is 5 advantageous in that the joints may be made where it is necessary to change the form of the member or ring 7.

As shown in Fig. 4, one side of the member 7 is drawn to correspond to the shape of the 10 joint between the strip 3 and ring 4, while the other side of said member 7 is swaged into a shape corresponding to that of the joint, as indicated in dotted lines.

In Fig. 5 the stiffening rings 4 are shown 15 as connected to the strips 3 by means of dovetailed grooves formed in the rings 4 embracing corresponding ribs on the strips 3. On one side of the central stiffening ring between it and the strip there is inserted 20 a securing ring 7 which has a dovetailed groove on each side embracing corresponding ribs on the ring and strip. Such connections are effected either in the manner indicated in Fig. 6, wherein the interior walls 25 of the groove are normally parallel and after the insertion of the rib of the strip said walls are pressed or swaged into contact with the sides of the rib, or said connection may be effected as illustrated in Fig. 7, wherein the 30 securing ring 7 has a flange on each edge, which is swaged down to conform to the configuration of the ribs on the sides of the strip and ring.

The provision of separate securing rings 35 is advantageous in that a joint may be more easily effected, where a considerable change is made in the form of the concentric edges or projections, than is possible where said ring is made integral with the stiffening 40 ring, because in order to get the necessary resistance against the centrifugal strains they

must be made of a comparatively hard material.

Experiments which have been made show that in cylindrical vane rings the joints in question may easily be made with the edges and projections in one piece with the stiffening rings, even if they are made of spring steel with 0.60 per cent. to 0.70 per cent. of carbon. If nickel steel be used a still larger 45 per cent. of carbon may be added, and in both cases stiffening rings of sufficient strength may be obtained.

It is evident that the separately arranged concentric edges or projections need not be 50 folded on the stiffening rings before they are secured in place, but the adjacent ribs may be so arranged that the parts are, by means of the folding, joined simultaneously.

I claim—

1. A unitary vane structure, comprising 55 a series of vanes, strips connected to the ends of said vanes and reinforcing rings in swaged connection with said strips.

2. A unitary vane structure, comprising 60 a plurality of vanes, a strip to which said vanes are connected, a reinforcing member for said strip and means associated therewith distorted to secure the reinforcing member and strip together.

3. A unitary vane structure, comprising 65 a series of vanes, strips fixed to the ends of said vanes having projections thereon, and reinforcing rings having projections adapted to be locked to the aforesaid projections.

In testimony, that I claim the foregoing 70 as my invention, I have signed my name in presence of two subscribing witnesses.

BIRGER LJUNGSTRÖM.
